(57) **CLAIM**

The ornamental design for an electric par lamp, as shown and described.

DESCRIPTION

FIG. 1 is a perspective view of an electric par lamp illustrating my new design;

FIG. 2 is a side view thereof;

FIG. 3 is another side view thereof;

FIG. 4 is still another side view thereof;

FIG. 5 is a front view thereof;

FIG. 6 is a rear view thereof; and,

FIG. 7 is a perspective view of another embodiment of an electric par lamp, with the only difference appearing in the swirl around the base portion.
